UNITED STATES PATENT OFFICE.

ARTHUR BURROUGHS EVANS, OF LEEDS, ENGLAND.

PRINTING MACHINE.

Application filed December 17, 1927, Serial No. 240,854, and in Great Britain June 16, 1926.

This invention relates to printing machines and especially to machines such as are used for printing on tin plates or sheets. In machines used for printing on tin plates or sheets, it has been usual for one operator to feed the plates or sheets by hand to the machine, either directly or by means of a semi-automatic apparatus by which the plate or sheet is fed by hand into a registering apparatus which conducts the plate or sheet to the printing part of the machine. Such a mechanism has the disadvantage that the maximum speed attainable by the machine is determined by the capacity of a single operator in handling the tin plates or sheets, and the invention has among its objects to avoid this disadvantage.

The object of the invention is to enable two operators alternately to feed the tin plates or sheets to the machine respectively on alternate cycles or operations of the machine under conditions whereby overlapping of the actions of the two operators, or of the movements of the plates or sheets presented by them to the machine, may be prevented.

According to the invention means are provided for arresting the sheet at the feed board such as described in the specification of the prior Patent No. 1,433,991, and in addition, one back lay and two side lays are provided having movements for registering the sheet at the front lays of the machine, as well as a detector motion by which the machine is tripped in the absence of a sheet, or alternatively in the case of a sheet being out of register on the feed board at the time it should be in register, for the reason, for example, that the sheet is too narrow, and, in addition, means are provided whereby the printing position will automatically be recovered in the machine on a sheet being correctly presented on the feed board.

According to the invention, moreover, means such as preliminary front lays, slightly in advance of the front lays of the machine, are provided to prevent any sheet from entering the machine before the front lays are in their "laying-on" position.

By such means the alternate action of the two operators may be determined, and two operators are enabled to feed sheets to one and the same machine which is running at double the usual speed.

The accompanying diagrammatic draw-

ings illustrate, by way of example, a construction of printing machine adapted for printing on tin plates or sheets and provided with the mechanism in accordance with the invention.

Figures 1 and 1^a together comprise a side elevation of the machine.

Figures 2 and 2^a together comprise a plan view of the machine, the impression cylinder being removed.

Figure 3 is a sectional elevation of the machine taken upon the line 3—3 of Figures 2 and 2^a.

Figure 4 is a cross-section of the machine taken on the line 4—4 of Figures 2 and 2^a.

Figure 5 is a detail cross-section illustrating the connection of the mechanism according to the invention with the tripping gear of the machine.

Figures 6, 7 and 8 are respectively side elevation, end elevation and plan of one of the side lays or back lays.

In carrying the invention into effect in accordance with the construction illustrated in the accompanying drawings, the feed plate *a* is provided with transverse slots *b* and a longitudinal slot *c* to serve as guides for the side lays *d* and the back lay *e* respectively. Each lay is provided with a runner *d¹, e¹* (Figures 6 and 8) respectively mounted upon the body of the lay in such manner as to be capable of limited movement in the direction of the length of the corresponding slot *b, c* respectively in the manner hereinafter fully described. Such movement is effected against spring pressure and the construction of the lays is such that the respective runners may be fixedly secured with reference to the corresponding lay body. The side lays *d* are respectively mounted upon bars *f* disposed below the corresponding slots *b* of the feed plate and mounted in bearings provided upon the underside of the feed plate so as to be capable of a reciprocatory movement. Similarly the back lay is mounted upon a bar *g* disposed below the slot *c* and adapted for a reciprocatory movement in the direction of the length of the slot.

The mechanism for effecting the necessary reciprocation of the side and back lays comprises a segmental lever *h* secured to a pivot pin *h²* (Figure 4) disposed in a position normal to the under face of the feed plate *a* and having secured to it an arm *h¹* operated by suitable cam mechanism from any

- convenient part of the mechanism of the printing machine; for example, as illustrated, the arm h^1 is oscillated by a connecting rod h^3 , connected to a swivel head on the 5 arm, the far end of the rod being pivoted to the free end of a lever h^4 fulcrumed at the side of the machine frame and carrying a runner or roller to engage a cam h^5 mounted upon the shaft z^1 of the printing cylinder z .
- 10 The segmental lever h is formed at the periphery with teeth adapted to engage a rack j^1 provided on a rack bar j mounted in bearings under the feed plate to permit longitudinal reciprocation and having rack 15 teeth for engagement with a pinion k mounted upon a spindle carrying a pinion d^2 for engagement with a series of rack teeth formed on the adjacent bar f . The pinion k also engages with a pinion l which 20 serves to effect reciprocation of the bar g by engagement with a series of rack teeth provided upon the adjacent lateral face of the bar. The opposite face of the bar is similarly provided with rack teeth for engagement with a pinion l^1 , which in turn 25 engages a pinion k^1 mounted upon a spindle carrying a pinion d^3 adapted to engage with rack teeth formed upon the second of the bars f . By such means it will be observed 30 that upon the angular reciprocation of the segmental lever h , the bars f and g will be reciprocated to effect the movement of the side and back lays d and e respectively between the positions indicated in Figures 2 35 and 2^a in full and dotted lines. Thus, if a sheet of tin or the like is placed upon the feed plate a during the time that the side lays d and the back lay e are at the outer limits of their travel, upon the return of 40 the lays to their inner limits of travel the sheet will be registered against the front lays m of the machine by the action of the back lay e and one of the side lays d , the second side lay d being set so that the runner 45 d^1 may have the relative movement with respect to the body of the lay hereinbefore referred to, and may thus set itself according to the position of the edge of the sheet of tin or the like.
- 50 The front lays m are mounted adjustably upon a shaft m^1 carried by the framework of the machine advantageously in movable bearings in such manner that the position of the shaft may be adjusted. The shaft has fixed 55 upon it an arm m^2 and is mounted under spring action tending to throw the lays m into the upper position. A shaft t is journaled in bearings in the machine framework and serves to carry by means of arms t^1 60 two rotatably mounted shafts s , s^1 serving respectively to support the elements of a number of sets of grippers. Thus, the inner shaft s carries a series of arms s^2 substantially radially disposed with respect to the shaft t and forming, by means of their heads,

the lower gripper surfaces, while the upper shaft s^1 serves to carry a corresponding number of co-operating gripper fingers s^4 adapted, when the grippers are closed by spring action tending to rotate the shaft s^1 , 70 to rest upon the heads before referred to and to form the upper gripper surfaces. Adjacent the frame on the one side, the shaft t has rotatably mounted upon it a fitting comprising three radially disposed arms t^2 , t^3 , t^4 , 75 to the lower of which, t^2 , is given a movement of oscillation in the manner hereinafter described. The upper arm t^4 serves to carry a pin m^3 adapted to engage with the arm m^2 for the depression of the lays m . Also rotatably mounted upon the shaft t adjacent the said fitting t^2 , t^3 , t^4 and adjustably secured to the arm t^2 by such means as an adjustable pin and slot connection, there is provided a cam plate formed with two cam surfaces s^5 , s^6 , one of which s^5 , acting as a bearing surface is adapted to engage with a runner s^7 mounted upon an arm secured to the shaft s and the other of which, s^6 , is adapted to engage with a runner s^8 carried by an arm secured to the shaft s^1 , so that according to the position of the fitting t^2 , t^3 , t^4 and when the sets of grippers are in the receiving position, the gripper fingers s^4 are raised to admit a sheet from the front lays m or are lowered to engage the sheet.

To effect the oscillatory movement of the grippers necessary for the feeding of the sheets to the impression cylinder z^3 , the shaft t is extended from the framework on the one side for the reception of a chain pulley t^5 around which is wrapped and secured a chain t^6 connected by a connecting rod t^7 to a swivel fitting mounted at the lower end of a lever t^8 fulcrumed upon the machine frame and carrying a runner t^9 adapted to engage a cam z^3 mounted upon the adjacent extremity of the impression cylinder shaft z^4 . The return movement of the chain pulley t^5 , and thus of the grippers to the receiving position, is effected by the action of a compression spring t^{10} disposed in a vertical position and anchored at the lower end to the machine frame and at the upper end to the chain pulley t^5 by means of pivoted telescopic rods or plungers, advantageously screw-threaded for the reception of nuts whereby the compression of the spring t^{10} may be varied.

In order that the grippers may be opened to release the sheet in the position in which the impression cylinder z^3 receives it, the shaft s^1 is also provided with an arm carrying a runner s^9 for engagement with a cam plate s^{10} secured adjustably in position upon the machine frame by means of bolts. The arm t^2 of the fitting t^2 , t^3 , t^4 carries a pin t^{11} with which is adapted to engage the hook portion of a claw lever v . The arm t^3 of the fitting is provided for connection with

a spring t^{12} tending always to rotate the fitting upon the shaft t in an anti-clockwise direction. This movement is limited, however, by means of a lug t^{13} upon the fitting 5 which is adapted to contact with an adjustable pin stop t^{14} mounted upon the machine frame. u is a fulcrum shaft extending across the machine frame and upon which is mounted a trip pedal u^4 . An arm u^1 is also 10 mounted upon the shaft u and is connected to a rod u^2 extending upwardly and passing loosely through a swivel fitting v^1 of the claw lever v , which is pivoted to a lever w fulcrumed upon the machine frame at w^1 15 and carries a runner for engagement with a cam w^2 mounted upon the adjacent end of the plate cylinder z or plate cylinder shaft z^1 . The cam thus rotates once in every cycle of the machine. A compression spring u^3 20 is mounted upon the rod u^2 between the swivel fitting v^1 and an adjustable collar upon the rod u^2 .

The claw lever v is engaged with or disengaged from the pin t^{11} according as the 25 trip pedal u^4 is raised or lowered at the appropriate time for engagement or disengagement, that is to say, when the lug t^{13} is engaging the stop t^{14} .

The detector mechanism, by which the 30 machine is tripped in the absence of a sheet or in the case where the sheet does not properly register against the front lays m , comprises a rod n mounted below the feed plate a in a position adjacent to, and parallel with, the bar g and in bearings such as to permit longitudinal movement thereof. A spring n^1 coiled around the rod between one of the 35 bearings and a collar upon the rod serves to press the rod n in the direction towards the rear of the plate a , where the rod is adapted to engage an arm n^2 upon a transverse rod n^3 carried in bearings fixed to the feed plate and having also an arm n^4 which is connected through a connecting rod n^5 with the 40 tripping mechanism of the printing machine. A bracket or arm e^2 connected to the runner e^1 of the back lay e is provided to embrace the rod n and to contact, on the forward movement of the back lay, with an 45 adjustable collar n^6 mounted upon the rod n so that the rod n is moved longitudinally and the tripping mechanism operated through the rod n^3 . It will be understood that when a sheet of tin is in position and 50 has been pushed into register with the front lays m by the back lay e the runner e^1 is moved rearwardly relatively to the body of the lay and the bracket or arm e^2 fails to contact with the collar n^6 , so that no tripping 55 of the machine takes place. When no sheet is present on the feed plate, however, or when the sheet fails to reach the front lays, for the reason, for example, that it is too narrow, the relative movement of the runner e^1 with respect to the body of the lay does

not take place so that the bracket or arm e^2 contacts with the collar n^6 and carries the rod n forward, whereby the tripping mechanism becomes operative.

The connection between the detector mechanism of the feed mechanism and the trip gear of the machine is advantageously provided according to the construction illustrated in the drawings. The rod n^5 is connected also to a bell crank lever p pivoted on the framework of the machine and carrying a depending member p^1 adapted always to engage by contact at one side with the lower arm of a bell crank lever q also pivoted on the framework and carrying a runner q^1 operated by a cam q^2 on the shaft z^4 . The lower arm of the lever q is curved or diverted to engage the depending member p^1 which is thus caused to swing at the required moment once in each cycle.

The depending member p^1 can also engage, on the "hit and miss" principle, with one arm r^1 of a three-armed lever r also pivoted on the framework and connected by a rod r^2 to mechanism co-operating with the trip mechanism of the machine. The three-armed lever r is mounted so that it is returned to its initial position, resting on a stop r^3 , by a spring r^4 .

The operation of the rod n^5 for tripping thus causes the member p^1 to be lowered so that when it swings under the action of the bell crank lever q it engages and throws over the three-armed lever r which effects movement of the rod r^2 as may be required, giving the effect that the trip pedal u^4 of the machine is held in the tripping position and the machine is tripped.

For the connection of this mechanism with the trip mechanism there is provided at the foot of the frame a bracket r^5 having two bosses or bearings r^6 , r^7 mutually at right angles and serving respectively as bearings for a spindle r^8 to which is secured at one end an arm r^9 connected with the rod r^2 by a connection which is adjustable, and at the other end an arm r^{10} , the extremity of which is disposed on the axis of the boss or bearing r^7 . The latter serves to receive a slidably mounted pin r^{11} mounted under spring action tending to throw it outwards towards the said arm r^{10} and having the forward end undercut or formed as an inclined or catch face. The said bracket r^5 is disposed immediately adjacent the trip pedal u^4 of the machine, which pedal is provided with a pivoted angular member u^5 comprising two arms, one of which lies below the arm of the pedal and is adapted to engage an adjusting screw u^6 , by which the position of the member u^5 may be adjusted, and the other arm u^7 of which is provided with a hook of a shape to correspond to the forward end of the pin r^{11} and is so disposed that in the movement of the pedal the hook passes be-

low the pin r^{11} . The member u^5 is maintained in its position of adjustment against the screw u^6 by means of a spring u^8 connected between the pedal arm and the arm u^7 of the member u^5 . The pedal u^4 is mounted upon the shaft u and is provided with an arm u^9 connected by a connecting rod u^{10} with a second arm u^{11} mounted upon a shaft u^{12} . Upon the connecting rod u^{10} there is provided an adjustable stop u^{13} . A cam x provided upon the shaft z^1 of the cylinder z serves by way of a runner to operate an arm x^1 which is carried upon a spindle x^2 mounted in the machine frame. This spindle, on the exterior of the frame, carries a second arm x^3 which is connected by a connecting rod x^4 with a bell-crank lever x^5 , the free arm of which is adapted to contact with the stop u^{13} on the connecting rod u^{10} . The connecting rod x^4 is mounted under the action of a spring x^6 tending to maintain the runner against the cam x and the bell-crank lever x^5 away from the stop u^{13} . The preliminary or auxiliary front lays o are positioned a short distance to the rear of the front lays m and are carried by levers o^1 carried by a spindle o^2 which is rocked or oscillated through the arm o^3 by a rod o^4 and a lever o^5 fulcrumed upon the machine frame and having a runner for operation by an adjustable cam o^6 on the shaft z^1 of the cylinder z . The lays o are adapted to project above the feed plate a immediately a sheet is passed, and to fall below the feed plate as the front lays m are moved into position to receive the succeeding sheet, the timing of this operation being effected by correct adjustment of the operating cam. An advantageous construction of the side and back lays is illustrated in Figures 6, 7 and 8. The body of the lay d is provided of channel shape and is supported upon the bar f by a channel shaped bracket d^4 which is clamped to the bar by means of a plate d^5 bolted to the bracket. One side of the bracket d^4 is provided of slightly less depth than the other, so that by means of an adjusting bolt d^6 the plate d^5 may be drawn tightly against the bar f to determine the position of the lay. A clamp d^7 constructed similarly to the bracket d^4 is mounted upon the bar f forward of the bracket d^4 and the two are connected together by means of a screwed pin d^8 which is received in lugs d^9 provided upon the plate d^5 of the bracket d^4 and the corresponding plate of the clamp d^7 . An adjusting nut d^{10} , secured upon the screwed pin, serves to determine the position of adjustment between the bracket d^4 and the clamp d^7 . The runner d^1 is rotatably mounted upon a vertically disposed pivot pin d^{11} carried by a plunger d^{12} which is slidably mounted within the body d and maintained

therein by means of a stop plate d^{13} and an end plate d^{14} . The runner is maintained in the forward position with reference to the body d by means of a helical spring d^{15} disposed within a bored recess in the plunger d^{12} . In order that the pressure of the spring may be adjusted, the end plate d^{14} carries a screwed pin d^{16} having a collar d^{17} against which the spring bears, so that by adjustment of the pin d^{16} in the end plate, the position of the collar d^{17} may be varied. The body d is closed by a cover plate d^{18} upon which is mounted the head or shield d^{19} which is of oblong, elliptical or oval shape. When it is desired that the plunger d^{12} should be secured within the body of the lay d so that the runner d^1 and the body d are not relatively movable, the screwed pin d^{20} is screwed home to engage the plunger in the position in which it is desired to be adjusted within the body d .

In the operation of the machine, during a complete cycle, a tin plate or sheet placed upon the feed plate a in proximity to the preliminary lays o is first fed forward into register with the front lays m by the side lays d and the back lay e . The movements of the side and back lays are effected by the mechanism as hereinbefore described operated from the cam h^5 , and on the forward movement of the plate or sheet under the action of the back lay e , the preliminary lays are lowered from the operative position by the mechanism as hereinbefore described operated from the cam o^6 . By the time the plate or sheet has arrived in register with the front lays m , the three armed fitting t^2 , t^3 t^4 will have been moved by the claw lever v under the action of the cam w^2 into the position where the lug t^{13} contacts with the pin stop t^{14} . In this position the cam surface s^6 will have engaged the runner s^8 in such manner as to open the gripper fingers s^4 and the pin m^3 will have moved to a position in which it has permitted the arm m^2 to rise to bring the front lays m into the operative position.

In the continuation of the cycle of operations, the three-armed fitting t^2 , t^3 , t^4 , is partially rotated by the claw lever v to move the cam surface s^6 away from the runner s^8 and to cause the pin m^3 to depress the arm m^2 . Thus the gripper fingers s^4 are permitted to fall to engage the plate or sheet upon the arms s^3 and simultaneously the front lays m are depressed. The chain wheel t^5 is now partially rotated by the action of the lever t^8 and the cam z^5 with the result that the shafts s and s^1 are revolved about the shaft t for the forward feed of the plate or sheet along the guides z^6 to the impression cylinder. By engagement of the runner s^9 with the cam plate s^{10} , the gripper fingers s^4 are caused to release their hold upon the plate or sheet and in the con-

tinued operation of the machine, the shafts s and s^1 are revolved in the reverse direction about the shaft t under the action of the spring t^{10} to the initial position to receive another plate or sheet. In the meantime the tripping of the mechanism of the machine is effected in the usual way and the cam x , the arms x^2 , x^3 , the connecting rod x^4 and the bell crank lever x^5 act upon the stop u^{13} to effect a depression of the trip pedal u^4 and thus the disengagement of the claw lever v from the pin t^{11} at the correct time. At the same time the cam q^2 acting upon the runner q^1 serves to oscillate the arm q , but inasmuch as the detector mechanism has not been operated, the three-armed lever r is not engaged by the depending member p^1 . When, however, there is a failure to feed a plate or sheet to the feed table or it is fed in such a way that it is improperly engaged by the side and back lays so that it fails to engage with the front lays m on the forward movement of the back lay e , the runner e^1 of the said lay is not moved relatively to the lay body e and accordingly the bracket e^2 engages the collar n^6 upon the rod n in the manner hereinbefore described. In these circumstances the depending member p^1 is depressed to the extent that upon the next oscillation of the lever q the lever r is rotated upon its pivot to throw forward the pin r^{11} so that this engages with the hook of the arm u^7 on the trip pedal u^4 and maintains this in the tripping position. When the trip pedal u^4 is depressed and held depressed the claw lever v is disengaged from the three-armed fitting t^2 , t^3 , t^4 so that this remains in the position with the lug t^{13} resting against the stop t^{14} and thus the gripper fingers s^4 will fail to close and the front lays m will not be withdrawn from the operative position until such time as the pin r^{11} is caused to release the trip pedal u^4 , by the action of its spring upon the next depression of the trip pedal by the cam x .

The mechanism hereinbefore described permits two operators to be employed on a single machine, each operator feeding sheets independently and alternately with his fellow to alternate cycles or operations of the machine, since each sheet correctly fed by the first operator is taken from the front lays by the feed grippers of the machine, and each sheet incorrectly fed by the first operator remains on the feed plate in full view of the second operator who therefore will refrain from feeding the machine till the sheet in question has either been registered or removed; further, when the first operator omits to feed a sheet the second operator, finding no interference, will continue feeding according to his proper cycle and the machine will automatically be tripped for each of the omitted sheets and returned to

the printing position in accordance with the action described.

It will be understood that the invention is not limited to the particular details of construction of the parts of the mechanism as hereinbefore described.

It will be understood that the side lays may be replaced by registering stops which may be of fixed position when the machine is used to operate upon plates or sheets of standard or determined dimensions.

I claim:

1. Printing machines and especially machines for the printing of tin plates and sheets, comprising a feed board, back and side lays movably mounted upon said feed board, means operating from the mechanism of the machine and acting upon the back and side lays to effect their reciprocation relatively to the feed board, movable front lays positioned in advance of the feed board, feed grippers mounted between the feed board and the impression cylinder, means operated from the mechanism of the machine for effecting the withdrawal of the front lays and the operation of the feed grippers, tripping mechanism applied to the front lays and the feed grippers, a detector element mounted upon the feed board for operation by the back lay thereon, and mechanism connecting the said detector element with the tripping mechanism, substantially as hereinbefore described.

2. Printing machines and especially machines for the printing of tin plates or sheets, comprising a feed board, slots in said feed board on lines disposed at right angles, back and side lays mounted to move in said slots, reciprocatory bars mounted below said feed board in line with said slots and supporting said back and side lays, means for reciprocating said bars operating from a rotatable element of the machine, front lays positioned in advance of the feed board, feed grippers mounted between the feed board and the impression cylinder, means operated from the mechanism of the machine for effecting the withdrawal of the front lays and the operation of the feed grippers, tripping mechanism applied to the front lays and the feed grippers, a detector element mounted upon the feed board for operation by the back lay thereon, and mechanism connecting the said detector element with the tripping mechanism, substantially as hereinbefore described.

3. Printing machines and especially machines for the printing of tin plates or sheets, comprising a feed board, slots in said feed board, back and side lays disposed respectively in said slots, reciprocatory bars upon which said back and side lays are mounted, rack teeth upon said bars, tooth gear engaging said rack teeth and

gearing said bars together, a reciprocating driving rack bar engaging and driving said gear, a fixed pivot pin, a toothed segment on said pivot engaging said driving rack bar, an arm upon said pivot pin, a cam upon a rotatable element of the machine, a lever engaging said cam, a rod connecting said lever with said arm, front lays positioned in advance of the feed board, feed grippers mounted between the feed board and the impression cylinder, means operated from the mechanism of the machine for effecting the withdrawal of the front lays and the operation of the feed grippers, tripping mechanism applied to the front lays and the feed grippers, a detector element mounted upon the feed board for operation by the back lay thereon, and mechanism connecting the said detector element with the tripping mechanism, substantially as hereinbefore described.

4. In printing machines and especially machines for the printing of tin plates or sheets, comprising tripping mechanism, a back lay adapted to reciprocate upon the feed board, means for operating said back lay, a detector member upon the said back lay relatively movable thereto, a movable control member lying adjacent the path of the back lay to contact with the detector member, a rotatable member driven from the mechanism of the machine, an oscillatory member oscillated by the said rotatable member, and a trip mechanism detaining member, mechanism for operating the said detaining member, the control member engaging said mechanism with the oscillatory member, substantially as hereinbefore described.

5. In printing machines, and especially machines for the printing of tin plates or sheets, comprising tripping mechanism, a gripper and front lay operating member, a reciprocating member engaging the said lay operating member, a rotatable member receiving movement from a rotary element of the machine and imparting motion to the reciprocating member, a tripping member engaging with the reciprocating member, a trip operating member connected with and serving to actuate the tripping member, a second rotatable member receiving movement from a rotary element of the machine, an oscillatory member engaging with and operated by the said second rotatable member, and a member connected with the said second oscillatory member and adapted to engage the trip operating member, substantially as hereinbefore described.

6. In printing machines, and especially machines for the printing of tin plates and sheets, provided with tripping mechanism, a feed board, a back lay movable upon said feed board, a detector member carried by said back lay, a control member disposed adjacent the path of the back lay and for

engagement with the detector member, a cam rotated from the machine mechanism, a lever oscillated by the said cam, a second lever disposed adjacent to but not engaging the first lever, a movable intermediate member connected with and moved by the control member and in one position engaging the two levers, and a tripping mechanism detaining member connected to and operated by the second lever, substantially as hereinbefore described.

7. Printing machines and especially machines for the printing of tin plates and sheets, comprising a feed board, back and side lays movably mounted upon said feed board, means operating from the mechanism of the machine and acting upon the back and side lays to effect their reciprocation relatively to the feed board, movable front lays positioned in advance of the feed board, preliminary front lays disposed between the back lay and the front lays, means operated from the mechanism of the machine effecting the movement of the preliminary front lays, substantially as hereinbefore described.

8. Printing machines and especially machines for the printing of tin plates and sheets, comprising a feed board, back and side lays movably mounted upon said feed board, means operating from the mechanism of the machine and acting upon the back and side lays to effect their reciprocation relatively to the feed board, movable front lays positioned in advance of the feed board, preliminary front lays positioned in openings in the feed board, a transversely disposed shaft rotatably carried by the machine, arms supporting the preliminary front lays and carried by the said shaft, an operating arm mounted upon the said shaft, a cam adapted to be rotated from a rotary element of the machine, a lever disposed adjacent to and operated by the said cam and a connecting rod between the said lever and the said operating rod, substantially as hereinbefore described.

9. Printing machines and especially machines for the printing of tin plates and sheets, comprising a feed board, back and side lays movably mounted upon said feed board, means operating from the mechanism of the machine and acting upon the back and side lays to effect their reciprocation relatively to the feed board, movable front lays positioned in advance of the feed board, a transverse shaft rotatably carried by the machine, feed grippers supported from the said shaft, an operating wheel secured to the said shaft, a cam adapted to be rotated from a rotary element of the machine, a lever adjacent to and oscillated by the said cam, a flexible member secured to the said wheel and connected to the said lever, a spring connected to the said wheel, an anchorage for the said spring provided upon the

machine frame, the said spring opposing the action of the lever, an oscillatory member mounted upon the said shaft and operating the feed grippers and the front lays, tripping mechanism applied to said oscillatory member, a detector element mounted upon the feed board for operation by the back lay thereof, and mechanism connecting the said detector element with the tripping mechanism, substantially as hereinbefore described.

10. Sheet feeding mechanism for printing machines and especially for machines for the printing of tin plates and sheets, comprising in combination a feed board, means 15 on the said feed board for registering a sheet thereon, means for feeding the said sheet from the said feed board to the grippers of the impression cylinder of the printing machine, a detector element co-operating 20 with the said means for registering a sheet to detect the absence of a sheet and the improper placing of a sheet upon the feed board, and tripping mechanism operated by the detector element to prevent the 25 operation of the said means for feeding sheets to the grippers of the impression cylinder of the printing machine, substantially as hereinbefore described.

11. Sheet feeding mechanism for printing 30 machines and especially for machines for

the printing of tin plates and sheets, comprising in combination a feed board, a back lay on the said feed board, means operating from the mechanism of the printing machine to effect the reciprocation of the said back lay to bring the sheet into register, movable front lays, sheet transfer mechanism adapted to carry a sheet from the feed board to the grippers of the impression cylinder of the printing machine, and detector mechanism operable from the said back lay and adapted to render the operation of the said sheet transfer mechanism ineffective, substantially as hereinbefore described.

12. Sheet feeding mechanism for printing machines and especially for machines for the printing of tin plates and sheets, comprising in combination a feed board, a back lay on the said feed board, means operating 45 from the mechanism of the printing machine to effect the reciprocation of the said back lay to bring a sheet into register, movable front lays, mechanism operated from the mechanism of the printing machine to prevent the transfer of the sheet from the feed board to the grippers of the impression cylinder when said sheet is not in register, substantially as hereinbefore described.

ARTHUR BURROUGHES EVANS.
